No. 876,348.

PATENTED JAN. 14, 1908.

T. HALL.

LOCK AND LATCH.

APPLICATION FILED APR. 6, 1906.

UNITED STATES PATENT OFFICE.

THOMAS HALL, OF NEW YORK, N. Y.

LOCK AND LATCH.

No. 876,348.

Specification of Letters Patent.

Patented Jan. 14, 1908.

Application filed April 6, 1906. Serial No. 310,216.

To all whom it may concern:

Be it known that I, THOMAS HALL, a citizen of the United States, residing at Brooklyn, county of Kings, city and State of New York, have invented certain new and useful Improvements in Locks and Latches, of which the following is a specification.

The object of this invention is to make a latch and lock, having little friction, simple in its mechanism, easy to apply either as mortise or rim lock, and adapted to swinging doors of different thicknesses.

The improvements consist principally in a double acting latch that moves easily when closing or opening the door, and by a new and simple device for locking the latch, also operating the latch by sliding the knob spindle instead of turning the knob in the usual way.

20 The double acting latch and the sliding spindle being the novel features, the mechanism connecting them can be varied in several ways; two forms are shown of the connecting mechanism between the spindle and the latch.

25 In the accompanying drawing forming part of this specification. Figure 1 is a sectional plan of lock and latch, inserted in wood work. Fig. 2 is an elevation from the outer side of door, with spindle in section. Fig. 3 is a sectional elevation of mortise lock. Fig. 4 is the inside handle or knob in the form of a bell. Fig. 5 is a section of spindle and locking lever. Fig. 6 is a sectional elevation from the inside. Fig. 7 is the outer knob or handle showing key-hole. Fig. 8 shows the connection between the spindle guide, and the frame of mortise lock. Fig. 9 shows a half mortise lock case having a modification 40 of mechanism for operating the latch.

Like figures refer to like parts.

In Fig. 1 is shown in section a mortise lock let into a door, having push and pull knobs in place and connected in operative condition 1 is a section of a door jamb, 2 is the door, 9 is the latch having pins 29 projecting from each side, shown in Fig. 1 as resting against the inside of the face plate, the other end of the latch at 28 rests on a ledge which is part of 45 face plate 27 and is held in that position at 25 by lever 18 fulcrumed at 19.

50 30 are curves on sides of latch case over which the pins 29 move, the radius point being at 25 on point of latch. Part of lever 18 extends above the fulcrum 19 and has opening 21. 20 is a push rod through 21. 23 is

a shoulder on the push rod for the spring to act against, 24 is a pivotal point in latch against which the push rod acts, 3 is a tube passing through a bored hole and immovably 60 fixed in the door, 6 is a tube revoluble in tube 3, 7 is a round spindle inside of tube 6 to which is fixed the outer knob 4 and the inner knob 5, 17 is a space cut out of the side of tube 3, 16 is a space cut out of inner tube 6, 65 into these spaces the end of lever 18 enters as at 34, 15 is a circular notch cut in the spindle 7 as shown (white) in Figs. 2 and 3, a portion of the lever 18 being let into the groove as at 34 in Figs. 1, 2, 3 and 8, 39 is a lever 70 fixed to the inner tube 6 movable in a slot in tube 3, a shoulder on the edge of the space 16 in tube 6 being formed so as to interfere with the movement of lever 18 by moving lever 39. A key, is shown, 12 with wards 13 75 designed to enter slit 11 in outer knob and act on inner tube 3 which operates to lock or unlock the movement of lever 18.

The operation of this mechanism is as follows. The latch swings in two directions 80 from different pivotal points, it has no fixed pivot. It is capable of turning or swinging on its bottom edge so that the latch moves inward when closing the door, the points 29 moving along the curved lines 30, or on opening 85 the door the latch turns on the points 29 and the lower end swings inward allowing the latch to move into the lock case. The spring 8 acts against lever 18 and against the latch between the pivotal points returning 90 the latch to its normal position both for opening and closing the door. The end of lever 18 bearing against the end of latch secures the latch so that the door can not open until the lever is moved to the position of the 95 dotted lines, when pressure on the latch will cause it to swing on points 29 and allow it to open. The lever 18 is controlled by the sliding of the spindle 7, the notch 15 carrying with it the end of lever 18. The knobs or 100 handles of the door are preferably on a round spindle and can turn freely without having any effect to open the door, the turning of the spindle being utilized for other purposes. To lock the door from the inside it is only necessary to turn the lever 39 which turns the tube 6, a portion of which comes in contact with the lever 18 and prevents it from moving. To lock the door from the outside the key is inserted through the knob into the spindle 105 and operates the tube 6 to lock or unlock the same as the lever 39 does on the inside. The

handle or knob of door lock does not directly act to move the latch, but releases the locking lever when pressure of the latch against the keeper forces the latch into the lock case 5. turning on its upper pivot.

Having described my invention what I desire to claim and protect by Letters Patent is:

1. In a lock and latch mechanism, a latch 10 having pivotal points at two of its extremities and held in normal position against both points, by a spring, substantially as shown.

2. In a lock and latch mechanism, a latch having two pivotal points at its extremities, 15 arranged to swing on either of the pivotal points, and mechanism to stop the swinging, substantially as shown.

3. In a lock and latch mechanism for a swinging door, a latch having two pivotal 20 points, the latch swinging on one point to open the door, and swinging on the other point when the door is closing, substantially as shown.

4. In a lock and latch mechanism, a swinging latch having two pivotal points and means for preventing it from swinging on one 25 of the pivots to prevent the door from opening, substantially as shown.

5. In a lock and latch mechanism, a latch 30 arranged to swing, to allow the door to close and to swing the opposite way when the door opens and means for preventing it from swinging, thereby securing the door from opening, substantially as shown.

35 6. In a lock and latch mechanism, a latch having two swinging movements on pivotal points at its extremities, a door knob or handle, and means for connecting the handle to the latch so as to control its action, substantially as shown.

7. In a lock and latch mechanism, a latch 40 and lock having knobs or handles on a sliding spindle, a double acting swinging latch hav-

ing two pivotal points and means for connecting the spindle to the latch, substantially 45 as shown.

8. In a door lock and latch mechanism, a latch having two pivotal points, a slideable spindle controlling the action of the latch, a stationary tube passing through the door 50 through which the slideable spindle moves, substantially as shown.

9. In a door lock and latch mechanism, a slideable spindle, an inner tube surrounding the spindle in an outer tube that is fixed 55 through the door, means for controlling the latch from the spindle and means for moving the inner tube so as to stop the movement of the spindle.

10. In a lock and latch mechanism, a latch 60 having two pivotal points, a spindle and means of controlling the movement of the latch by the spindle.

11. In a lock and latch mechanism, a swinging latch, a sliding spindle arranged to 65 operate the latch, a tube inclosing the spindle, means for stopping the sliding of the spindle by rotating the tube.

12. In a lock and latch mechanism, a swinging latch, a sliding spindle arranged to 70 operate the latch, a tube inclosing the spindle, means for stopping the sliding of the spindle by rotating the tube and means for rotating the tube by a key, substantially as shown.

75 13. In a lock and latch mechanism, a sliding spindle for operating a latch, a rotatable tube inclosing the spindle, a fixed tube inclosing the rotatable tube, a key adapted to enter the fixed tube and move the rotatable 80 tube.

THOS. HALL.
